PLATFORM SHOE

William Michael Fennessy, Carlisle, Pa., assignor
to Carlisle Shoe Company, Carlisle, Pa., a cor-
poration of Pennsylvania

Application October 1, 1946, Serial No. 700,432

3 Claims. (Cl. 36—19.5)

1

The present invention relates to shoes and to a method of making them.

The primary object of this invention is the provision of a slip-lasted shoe with an extension edge forepart platform embodying the welt principle of stitching whereby to produce a slip-lasted shoe which is improved appearance and which is characterized by greater durability and improved flexibility in the forward part thereof.

The above and other objects, features and advantages of the invention will be fully understood from the following description considered in connection with the accompanying illustrative drawings:

In the drawings:

Fig. 1 is a longitudinal sectional view of a lady's shoe embodying the present invention;

Fig. 2 is a top plan view of a front portion of the shoe;

Fig. 3 is a bottom plan view of the forepart of the shoe;

Fig. 4 is a sectional view on the line 4—4 of Fig. 1;

Fig. 5 is an exploded perspective view of parts of the shoe;

Fig. 6 is a view similar to Fig. 4, without the middle and outer soles attached and with a last inserted.

Referring now to the drawings in detail the shoe embodying the present invention comprises an upper 10, a thin insole 12, a forepart middle sole or platform 14, a shank member 16 provided with a metal stiffener 18, a platform cover 20, an outer sole 22, and a heel 24. As here shown, the upper 10 is of the open heel and toe type, but it will be understood that said upper can be of any other type. Also, as shown the upper which is preferably made of leather, but which can be made of fabric or any other suitable material, is illustrated as consisting of a single thickness of material but it will be understood that the upper may be provided with the usual lining which customarily is cemented to the inner surface of the outer layer of the upper, or said upper may consist of a single thickness of suitable material provided with an edge binding around the foot opening, as will be readily understood. The insole 12 is preferably formed of a layer 23 of soft and thin material such as, for example, split leather, and a covering layer 25 of fabric or other suitable material, the rear portion of said insole being also provided with a thin heel-seat cover 39. The forepart middle sole 14 is preferably made of sole leather but can be made of any other suitable material and likewise the shank member 16 is preferably made of leather but can be made of any other suit-

2

able material. Similarly the outer sole 22 can be made of sole leather or of any other suitable material. It will be understood that the platform cover 20 can be made of shoe upper leather or of any other suitable material and may match or contrast in appearance with the material of the upper 10.

In accordance with the present invention the upper 10 is cut to the exact size and shape which it has in the finished shoe, and the insole 12 is shaped to the exact contour of the bottom of the last for the particular shoe. This upper and insole, together with the platform cover 20 are stitched to each other preferably by a single line 15 of stitching 32 which passes through the upper, insole and platform cover as illustrated in Fig. 6, the outer surface of the platform cover 20 lying next to the outer surface of the marginal edge portion of the upper 10 and the inner surface 20 of the upper 10 lying next to the outer surface of the marginal edge portion of the insole 12.

After the upper insole and platform cover are stitched together, the last is inserted as indicated at L in Fig. 6. Then the forepart platform 14 is placed on the bottom of the shoe, abutting the adjacent surface of the insole, said middle sole or forepart platform 14 extending from the ball line of the shoe to the toe. This platform or middle sole 14 is of such width that it extends a substantial distance, say $\frac{1}{4}$ of an inch, laterally outwardly beyond the lower edge of the upper 10, i. e., laterally outwardly beyond the crease line 34 of the shoe. The shank member 16 with the attached stiffener 18 is placed in position, and it will be understood that the forepart platform 14 and the shank member 16 are secured in position preferably by cement. When the cement is dry the platform cover 20 is stretched over middle sole 14 and shank member 16 and folded over the marginal edge portion of said middle sole and shank member and adhesively secured thereto at the bottom of the shoe.

The outer sole 22 is then applied in position 45 over the folded over marginal edge portion 36 of the platform cover which extends completely around the shoe, as can be readily understood, and said outer sole is secured in position, the heel and shank portions of the outer sole being 50 adhesively secured to the corresponding adjacent surfaces of the shank member 16 and the infolded marginal edge portion 36 of the platform cover. In accordance with the present invention the forepart of the outer sole 22, that is the part 55 which extends forwardly from about the ball line of the shoe to the toe thereof, is secured by a line 38 of Goodyear stitching passing through the

platform cover 20, the mid sole or platform 14 and the outer sole 22. It will be understood that said forepart of outer sole 22 conforms to the peripheral curvature of the platform 14 and extends preferably slightly beyond the outer peripheral edge of the latter. The line of Goodyear stitching 38 extends from a point at one side of the shoe substantially at the ball line as indicated at 40 forwardly of the shoe to a point at the other side of the shoe substantially at the ball line as indicated at 42, said line of stitching being disposed between the crease line 34 of the shoe and the outer peripheral edge of the forepart of the outer sole 22 or forepart of the bottom of the shoe. Preferably said line of stitching 38 is disposed about $\frac{1}{8}$ of an inch from the outer edge of the forepart of the bottom of the shoe. It will be understood that the forepart of the outer sole 22 need not be cemented to the adjacent surface of the platform 14 or to the infolded portion 36 of the platform cover at the forepart of the shoe, but that, on the other hand, it is within the scope of the present invention to adhesively secure said forepart or outer sole 22 to said platform 14 and the corresponding infolded portion 36 of the platform cover.

It will be noted that as shown in Fig. 6, the lasting allowance or inner marginal edge portion of the upper and the inner marginal edge portion of platform cover 20 together with the stitching 32 are located at the bottom of the last inwardly of the edge of the latter and lie substantially flatly against the upper surface of the middle sole. This results in the location of the stitching 32, the lasting allowance of the upper and the inner edge of platform cover 20 inwardly of the crease line 34 of the shoe in position between the upper surface of middle sole 14 and insole 12. Accordingly, when the outsole 22 is stitched through the middle sole, as described, there is no visible seam or stitching at the bottom of the shoe other than the Goodyear stitching 38 through the middle sole, platform cover, and outer sole.

It will be understood that the invention may be varied in various ways in respect to the details of construction, the materials utilized and in the details of the method without departing from the underlying idea or principles of the invention within the scope of the appended claims.

Having thus described my invention, what I claim and desire to secure by Letters Patent is:

1. In a shoe having an upper, an insole, and a platform cover stitched together, a middle sole secured in position and encased by said platform cover, the latter having a top marginal edge portion positioned at the top of said middle sole and having a lower marginal edge portion folded inwardly over said middle sole at the bottom thereof, said upper having a marginal edge portion underlying the marginal edge portion of said insole, said marginal edge portion of the upper, said top edge portion of said platform cover and said stitching being disposed inwardly of the crease line of the shoe and lying substantially flatly against the upper surface of said middle sole and said middle sole having its upper surface abutting the under side of said insole, an outer sole, and means for securing said outer sole in position including a line of stitching through said platform cover, middle sole and outer sole at the outerside of the crease line of the shoe.

2. In a shoe having an upper, an insole, and a platform cover stitched together, a middle sole

secured in position and encased by said platform cover, the latter having a top marginal edge portion positioned at the top of said middle sole and having a lower marginal edge portion folded inwardly over said middle sole at the bottom thereof, said upper having a marginal edge portion underlying the marginal edge portion of said insole, said marginal edge portion of the upper, said top edge portion of said platform cover and said stitching being disposed inwardly of the crease line of the shoe and lying substantially flatly against the upper surface of said middle sole and said middle sole having its upper surface abutting the under side of said insole, an outer sole, and means for securing said outer sole in position including a line of stitching through said platform cover, middle sole and outer sole, said middle sole having its rear edge substantially at the ball line of the shoe and said line of stitching terminating at substantially the ball line of the shoe and being disposed between the crease line of the shoe and the outer peripheral edge of the outer sole.

3. In a shoe having an upper, an insole, and a platform cover stitched together, a middle sole and a separate shank piece with a stiffener secured in position, the adjacent ends of said shank piece and middle sole being located substantially at the ball line of the shoe, said middle sole and shank piece being encased by said platform cover, the latter having a top marginal edge portion positioned at the top of said middle sole and having a lower marginal edge portion folded over and secured to said middle sole, said upper having a marginal edge portion underlying the marginal edge portion of said insole, said marginal edge portion of the upper, the inner edge portion of said platform cover and said stitching being disposed inwardly of the crease line of the shoe and lying substantially flatly against the upper surface of said middle sole and said middle sole having its upper surface abutting the under side of said insole, an outer sole, and means for securing said outer sole in position including a line of stitching through said platform cover, middle sole and outer sole, said line of stitching being disposed between the crease line of the shoe and the outer peripheral edge of the outer sole.

50 WILLIAM MICHAEL FENNESSY.
